(57)

CLAIM

The ornamental design for a charger, as shown and described.

DESCRIPTION

FIG. 1 is a front perspective view of a charger showing my design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof; and,

FIG. 7 is a bottom plan view thereof.

The broken lines in the drawings are employed to show unclaimed portions of the charger, and form no part of the claimed design.

1 Claim, 7 Drawing Sheets(56)
